INVENTOR:

ZACHARIA ROUTTENBERG,
BY John de Ruiter.

HIS ATTORNEY.

UNITED STATES PATENT OFFICE

ZACHARIA ROUTTENBERG, OF LOS ANGELES, CALIFORNIA

SEWING MACHINE NEEDLE-PLATE

Application filed January 20, 1930. Serial No. 422,047.

This invention relates to devices designed to cover a comparatively large opening above the shuttle and above the feed mechanism being at the same time the guiding means for 5 the feed member that extends through this plate to the surface over which the cloth and the like is handled for sewing purposes.

One of the objects of this invention is to provide a needle plate designed to stay in its 10 place, having suitable provisions made by which various removable parts can be applied for cutting narrower or broader edges alongside of the stitching point of the plate.

Another object is to provide an exchangeable member as a comparatively small part 15 of the needle-plate, to take care of any variation in the setting and spacing of the cutting blade in relation to the needle in a sewing machine, this invention involving a special 20 needle-plate particularly designed for that type of sewing machines used for a combined edge-cutting and sewing.

Another object is to provide a changeable 25 needle-plate in which the top surface is flush with the surrounding surface of the sewing machine top-plate and smooth in itself with respect to the several parts embodied in this plate.

Other objects will appear from the following description and appended claim as 30 well as from the accompanying drawing, in which—

Fig. 1 is a top plan view of a needle-plate 35 of a sewing machine, illustrating the outline and position of an exchangeable insert by which the cutting edge, to cooperate with the cutting edge of a movable cutting blade, can be arranged at various distances in regard to the needle-hole in the needle-plate and therewith in relation to the needle of a sewing machine to which the needle-plate is applied.

Fig. 2 is a section on line 2—2 of the combination needle and cutting plate illustrated 40 in Fig. 1.

Fig. 3 is a top plan view of a cutting insert 45 in a slightly modified form in which a cutting edge has been provided to be farther away from the stitching line than in the arrangement illustrated in Fig. 1.

Fig. 4 is a section on line 4—4 of the insert illustrated in Fig. 3.

As illustrated in the drawing, the larger portion 5 of the needle-plate is of the general outline necessitated by the opening left for this purpose in different sewing machines, and this outline may therefore vary considerably, depending on the openings of the different sewing machines. The aperture 6 for the feed-member 7 may also be of different 55 shapes. The hole 8 serves as a passage for the needle of the sewing machine.

Any material, such as cloth and the like, is normally placed over the feed-member 7 in a suitable relation to the needle-hole 8, to receive a desired stitching along a required line 60 with regard to the needle-hole.

The edge of the material sidewise of such a stitching is frequently to be trimmed or 65 cut, and certain combination sewing and cutting machines have been developed for this purpose.

On different articles or goods the trimmed edge, however, is desired more or less wide, and since the cutting blade in such machines 70 is made to be adjusted to designed variations for cutting different edges, the cooperating cutting-edge or portion in the needle-plate 75 must be changeable accordingly.

To avoid the necessity of changing the whole needle-plate as is the common practice, the principal feature surrounding this invention is therefore to design the needle-plate proper to remain in its place within the sewing machine after having once been 80 installed, and to provide a comparatively small exchangeable member to take care of the variations due to different settings of the cutting blade that is cooperating with the needle of the sewing machine.

The needle-plate proper 5 is for this purpose recessed as indicated in Fig. 1 by the lines 9 to a depth indicated in Fig. 2 at 10, to receive an insert 11.

To properly engage and place this insert, 95 on the one hand, and to provide sufficient material in the insert for a suitable depth for the necessary cut for the cooperating moving cutting blade, on the other hand, a deeper recess or cut-out 12 extends below the first-described 100

recess to take care of the heavier portion 13 of the insert.

A screw 14 serves to hold the insert in its proper place within the needle-plate proper 5.

6 While for close cutting the cooperating cutting-blade may cut against a portion 15 of the edge around the first-described recess requiring merely a recess or cut-out in the 10 end of the insert as indicated at 16, when the edge is to be cut wider the recess is provided within the insert at any suitable point, as for instance, indicated at 17 in Figs. 3 and 4, forming the cutting edge 18.

15 To safeguard against any clogging up of the cutting recess, and to facilitate the removal of waste material from the cutting recess, a slanting extension recess 19 is provided in the insert.

20 Having thus described my invention, I claim:—

In an attachment of the class described, a needle-plate having a recess with an adjoining aperture besides the apertures for a feed member and for a sewing-needle, and an insert fitting in said recess and having a shouldered portion extending downwardly to engage in said adjoining aperture, the top of the insert being flush with the top of the said plate, and the insert being recessed whereby a cutting edge is formed in the top of the insert along a line in the direction in which material is normally fed over the plate and sidewise of the said aperture for the needle.

35 In testimony that I claim the foregoing as my invention I have signed my name.

ZACHARIA ROUTTENBERG.
